UNITED STATES PATENT OFFICE.

CORNELIUS E. HAYNES, OF BOSTON, MASSACHUSETTS.

BOILER.

SPECIFICATION forming part of Letters Patent No. 245,822, dated August 16, 1881.

Application filed February 14, 1881. (No model.)

To all whom it may concern:

Be it known that I, CORNELIUS E. HAYNES, of Boston, in the county of Suffolk and State of Massachusetts, have invented an Improvement in Boilers, of which the following is a full, clear, and exact description, reference being had to the accompanying drawings, making part of this specification, in which—

Figure 1 is an elevation of a boiler constructed in accordance with my invention. Fig. 2 is a vertical section through the same. Fig. 3 is a transverse section.

The object of my invention is to produce a boiler for hot water and other purposes at a much less cost than heretofore; and it consists in certain details of construction which will be hereinafter more particularly described and specifically claimed.

In the drawings, A represents a boiler for supplying hot water to the different apartments of a building. This boiler, which is made of metal, is corrugated or fluted, as shown—to wit, from end to end in straight and parallel lines and all round—for the purpose of resisting the internal pressure of water or steam or external pressure caused by a vacuum formed within it. The top a of this boiler A is provided with a flange, b, which projects down over the main portion, and is secured thereto by rivets or solder, as may be found most desirable.

The bottom c, which has a corrugated edge to match with and tightly fit into the corrugations of the boiler, is secured to the main portion of the boiler A by means of bolts or rivets passing through the flange d of the bottom c, which projects down on the inside of the main portion A, and it will be seen that by this construction the bottom c can easily be removed when required to make repairs, and also to obtain access to the interior of the boiler.

The rings or braces f have corrugated edges to fit the corrugations of the boiler, and are placed upon the inside of the boiler and se-

cured thereto in any suitable manner, for the purpose of strengthening the boiler when made of thin material, and also to serve the purpose of keeping the boiler in its proper shape. In practice I have found that by making the corrugations as shown in Fig. 3—that is, one large and one small alternately—it greatly adds to the strength of the boiler in resisting pressure from within, and also serves to retain the boiler in its proper shape.

A boiler constructed as above described can be easily and cheaply made and is exceedingly strong and durable. Furthermore, much thinner and lighter material can be employed in its construction than has heretofore been found practicable, while it will withstand a much greater pressure outwardly or inwardly per square inch than boilers of the old construction.

I am aware that the broad idea of corrugating a steam-boiler is not new, and that sectional boilers have been corrugated at right angles with their length, and other boilers have been corrugated in some degree horizontally, and also some spirally, and also that internal strengthening-bands have been used in such boilers.

What I claim is as follows:

1. The boiler A, corrugated from end to end in parallel lines, and provided with the internal annular brace, f, having a corrugated edge, substantially as shown and described.

2. The boiler A, corrugated in parallel lines from end to end and entirely around, and provided with the internal annular strengthening-brace, f, as described, and the bottom c, having a corrugated edge, all substantially as described.

Boston, January 29, 1881.

CORNELIUS E. HAYNES.

In presence of—

W. J. CAMBRIDGE,
L. C. SOUTHDARD.
